[57] ABSTRACT

A table especially adapted for use in the assembly of jigsaw puzzles is described. The table comprises a horizontal planar surface or top supported by four legs. Attached to the top are a pair of leafs or piece trays. The piece trays are attached in a manner such that they remain parallel to the top when moved outwardly with respect to the top. In addition, covers are provided for covering the piece trays. When the piece trays are moved inwardly so that they overlie the top; the covers are attached; and, the legs folded, the puzzle assembly table is collapsed to a size convenient for storage. When thusly collapsed, the lower surface of the piece trays maintain the assembled portion of the puzzle in its assembled state while the covers retain the unassembled jigsaw puzzle pieces firmly in the piece trays.

FIG. 5

JIGSAW PUZZLE ASSEMBLY APPARATUS

BACKGROUND OF THE INVENTION

This invention relates to assembly tables and more particularly to an assembly table especially adapted for use in the assembly of jigsaw puzzles.

A popular leisure-time activity is the assembly of jigsaw puzzles. A jigsaw puzzle is formed of a plurality of pieces, usually made of cardboard, cut in irregular patterns. When the pieces are assembled in the correct manner, they interlock together and display a scene or picture. Thus, they are also known as picture puzzles.

In the past jigsaw puzzles have been assembled on any suitable horizontal surface, such as a kitchen or dining room table, or a "card" table. While such tables are suitable for assembling jigsaw puzzles, they have certain disadvantages. For example, it frequently takes several hours to assemble jigsaw puzzles, even if several people are assisting in the assembly. Thus, it is often necessary to assemble the puzzle during different, separated periods of time. If such is the case, obviously, it is inconvenient to assemble the puzzle on a dining room or kitchen table because those tables must be used for other purposes. In addition, it is inconvenient to assemble the puzzle on a "card" table if space is limited, such as in a house trailer, for example. Thus, in the past, it has been often necessary to "break up" a partially assembled puzzle in order to utilize the surface on which it is being assembled for other purposes. When this situation occurs, the "broken up" puzzle must be reassembled at a later date. Consequently, it is desirable to have a table that is especially adapted for the assembly of jigsaw puzzles. It is also desirable to have a table that can store a partially assembled jigsaw puzzle without requiring that it be broken up prior to storage.

Therefor, it is an object of this invention to provide a puzzle assembly apparatus.

It is a further object of this invention to provide a new and improved assembly table especially adapted for the assembly of jigsaw puzzles.

It is still another object of this invention to provide a jigsaw assembly table that is suitable for storing a partially assembled jigsaw puzzle.

SUMMARY OF THE INVENTION

In accordance with principles of this invention a jigsaw puzzle assembly table is provided. The table generally comprises a horizontal planar surface or top. Preferably the top is supported by four legs which collapse in a manner similar to the way the legs of a card table collapse. At least one leaf or piece tray is attached to the top in a manner such that it lies atop when in a closed position and extends outwardly from the top when in an open position. Movement of the piece tray from a closed position to an open position is performed in a manner such that the piece tray always lies in a plane that is parallel to the plane of the top. The piece tray provides a receptacle suitable for storing pieces of a jigsaw puzzle prior to assembly, the puzzle being assembled on the upper surface of the top.

In accordance with other principles of this invention, a pair of piece trays are provided and attached to the top by parallel bars which maintain the piece trays in planes parallel to the plane of the top during movement between open and closed positions.

In accordance with further principles of this invention, covers are provided and used to cover the piece trays in a manner such that jigsaw puzzle pieces lying in the piece trays are firmly retained therein when the covers are attached. In addition, the piece trays are formed such that their lower surfaces press against a partially assembled puzzle lying on the upper surface of the top in a manner such that the partially assembled puzzle is rigidly pressed against the upper surface of the top. Thus, when the assembly table is collapsed and stored the puzzle pieces are held immobile. Further, a variety of hooks and clips are provided to maintain the piece trays and the covers in the desired positions during storage.

15 It will be appreciated from the foregoing summary that a novel jigsaw puzzle assembly table is provided by the invention. The puzzle assembly table is formed such that a puzzle can be partially assembled on a main horizontal planar surface or top. The partially assembled 20 puzzle can be maintained in its assembled position by moving piece trays to a closed position where they overlie the top. In addition, puzzle pieces lying in the piece trays are maintained snugly in position by the use of covers. Thus, both the partially assembled puzzle 25 and the pieces are fixedly retained when the overall table is "closed". The overall table can then be collapsed for ease of storage without the partially assembled puzzle or puzzle pieces moving from their housed positions. Hence, the invention overcomes the two 30 prior art problems discussed above. More specifically, the puzzle does not have to be disassembled prior to storage. In addition, the assembly table can be reduced to a relatively small size for easy storage.

BRIEF DESCRIPTION OF THE DRAWINGS

The foregoing objects and many of the attendant advantages of this invention will become better appreciated from the following detailed description of a preferred embodiment of the invention when taken in conjunction with the accompanying drawings wherein:

FIG. 1 is a perspective view illustrating a puzzle assembly table formed in accordance with the invention with the piece trays in a closed position;

FIG. 2 is a perspective view of a puzzle assembly table of the type illustrated in FIG. 1 entirely closed for storage;

FIG. 3 is a partial perspective view of a puzzle assembly table of the type illustrated in FIG. 1 with the piece trays shown closed and the covers shown removed;

FIG. 4 is a partially perspective view of a puzzle assembly table of the type illustrated in FIG. 1 with the piece trays partially open;

FIG. 5 is a bottom perspective view of the piece trays in the position illustrated in FIG. 4; and,

FIG. 6 is a partial perspective view of the piece trays in their full open position.

DESCRIPTION OF THE PREFERRED EMBODIMENT

Turning now to the drawings wherein like reference numerals designate like parts throughout the several views, the figures illustrate a preferred embodiment of the invention and are organized such that they illustrate the preferred embodiment of the invention in a closed, open or partially open configuration.

FIG. 1 illustrates a preferred embodiment of the invention which comprises a horizontal planar surface or

top 11 supported by four legs 13 shown extended downwardly. As illustrated by the dashed line, the legs 13 can be folded toward the top, in the manner that the legs of a card table fold, to provide a compact collapsed structure of the type illustrated in FIG. 2.

As illustrated in FIGS. 4, 5 and 6 the top 11 comprises a rectangular planar surface 15 surrounded by four edge strips 17 which are raised above the rectangular planar surface 15. As illustrated in FIG. 6, the planar surface 15 is suitable for supporting an assembled or partially assembled jigsaw puzzle 19.

First and second piece trays 21 and 23 are attached to a parallel pair of the edge strips 17, surrounding the planar surface 15 forming the top 11, by sets of parallel bars 25. More specifically, each piece tray 21 and 23 is formed of a planar surface 29 surrounded by four edge strips 27. Certain of the edge strips 27 of the two piece trays 21 and 23 are arrayed such that they are aligned with and lie atop the upper surface of the edge strips 17 surrounding the rectangular planar surface 15. Thus, the entire top 11 is covered by the piece trays 21 and 23. The edge strips 27 and piece tray planar surfaces 29 are attached such that wells are formed in which jigsaw puzzle pieces 31 can be arrayed.

The edge strips 27 of the piece trays 27 located adjacent to a pair of parallel edge strips 17 forming part of the top 11 are attached thereto by the parallel bars 25. More specifically, each piece tray, as illustrated in the drawing covers one-half of the top 11. Thus, a pair of parallel edge strips of each piece tray are adjacent to a pair of parallel edge strips of the top. These adjacent edge strips are attached to one another by parallel bars — a pair of bars on either side of each piece tray. This parallel bar arrangement allows the piece tray 21 and 23 to be moved outwardly from a closed position (FIG. 1, 2 and 3) to an open position (FIG. 6) with the upper surface of the piece trays being maintained parallel to the upper surface of the top during the entire period of movement (FIGS. 4 and 5).

Located on the underside of each piece tray 21 and 23 is a pad 33 (FIG. 5). The edge of the pads are set-back from the edges of the piece trays 21 and 23 in a manner such that they fit inside of the edge strips 17 of the top 11 when the piece trays lie atop of the top. When in this "closed" position, the pads press tightly against the assembled or partially assembled puzzle 19 to thereby fixedly retain the puzzle in this position. Thus, a partially assembled puzzle is fixedly retained in position when the jigsaw puzzle assembly table of the invention is entirely collapsed to the compact state illustrated in FIG. 2. In the collapsed state, the table is suitable for easy storage. Moreover, because of previously described position retaining function provided by the invention, the collapsed table does not have to be maintained in a horizontal plane during storage, rather, the table can be stored with the top lying in a vertical plane.

The sets of parallel bars 25 are locked in the open or closed positions by clips 35 which slip over the parallel bars when they are in either the full open or full closed positions. The clips prevent the sets of parallel bars from separating from one another as occurs when the piece trays are moved from the open position to the closed position and vice versa (see FIGS. 4 and 5).

Covers 37, formed of planar members 39, are utilized to enclose the wells in the piece trays 21 and 23. More specifically, the covers 37, in addition to the planar

members 39 include pads 41 affixed to their lower surfaces but set-back there from. More specifically, the planar members and pads making up the covers are formed such that the edges of the planar members coincide with the edges of the edge strips 27 of the piece trays when the covers lie atop the piece trays. The pads 41 fit down into the wells in the piece trays and press against the jigsaw puzzle pieces 31 lying in the piece trays in the same manner that the pads 33 located beneath the piece trays press against the partially assembled puzzle 19.

Catch pins 43 attached to the undersurface of the planar surface 37 forming part of the covers coact with catch receptacles 45 attached in the wells of the piece trays 21 in a manner such that the covers are affixed in place when they lie atop the piece trays 21 and 23. The catches may take on any suitable form. For example, they may be catches of the type used to retain cupboard doors closed. In other words, they can be mechanical catches or they may be magnetic catches. In addition, a pair of hooks 47 attach the covers 37 together where they join one another. Further hooks 49 attach the piece trays 21 and 23 to the top 11 when the piece trays are in this closed position. Finally, U-shaped clips 51 that fit over the junction between the covers 37 and the lower surface of the rail 17 of the top 11 are used to assist in maintaining the overall system closed during storage. In addition, if desired, a suitable zippered cloth cover (not shown) can be used to cover the overall collapsed jigsaw puzzle assembly table during storage. That is, when the puzzle assembly table is entirely collapsed as illustrated in FIG. 2 a suitable cloth cover can be utilized to enclose the table and further prevent the table from opening. In addition, the cover will prevent the table from being nicked or scratched during storage as well as prevent the table from nicking or scratching something else. Finally, a handle 53 is attached to the overall structure at a suitable point to allow it to be carried in the manner an attache case is carried.

It will be appreciated from the foregoing description of a preferred embodiment of the invention that a jigsaw puzzle assembly table is provided. The assembly table is easily collapsed into a state that is suitable for storage. In addition, a partially assembled puzzle can be stored without the puzzle breaking apart either through the intentional operations of the puzzle assemblers or because of the physical characteristics of the table. That is, a partially assembled puzzle, as illustrated in FIG. 6, is firmly held in position when the piece trays are closed to the positions illustrated in FIGS. 1, 2 and 3. Moreover, pieces lying in the piece trays are fixedly held in position by the covers 37 when they are closed in the manner illustrated in FIGS. 4 and 2. Thus, both the pieces and the partially assembled jigsaw puzzle are prevented from movement during storage, even if the jigsaw puzzle assembly table is stored in the vertical position illustrated in FIG. 2.

While a preferred embodiment of the invention has been illustrated and described, it will be appreciated by those skilled in the art and others that various modifications can be made therein without departing from the spirit and scope of the invention. For example, if it is desired to rest the assembly apparatus on another horizontal surface, such as a table, for example, the legs may be eliminated. Alternatively, the legs may be reduced in length if it is desired to rest the assembly appa-

ratus on another horizontal surface but raised therefrom, such as about a patient's body in a hospital bed, for example. Moreover, the legs may be slightly shorter in the "front" than in the "rear" if desired so as to allow the patient to more easily view the puzzle from a reclining position. Hence, the invention can be practiced otherwise than as specifically described herein.

The embodiments of the invention in which an exclusive property or privilege is claimed are defined as follows:

I claim:

1. A jigsaw puzzle assembly apparatus comprising: an assembly surface having a pad thereon suitable for supporting a jigsaw puzzle in a horizontal plane during assembly; a flat piece-tray means suitable for supporting jigsaw puzzle pieces on a top surface thereof, said piece-tray means comprising two pads, one pad being located on a bottom surface thereof; and, an attachment means for attaching said piece-tray means to said assembly surface in a manner such that said piece-tray means is movable between a closed position where it lies atop said assembly surface with said bottom surface of said piece-tray contacting said assembly surface while said top surface of said piece-tray means is for supporting said jigsaw puzzle pieces, and an open position, where it is separated from, but adjacent to, said assembly surface and where said top surface thereof is still for supporting puzzle pieces, said attaching means comprising at least two sets of parallel bars attaching said piece-tray to said assembly surface in such a manner that said piece-tray means is maintained parallel to said assembly surface while said piece-tray means is moved between said closed and open positions, said piece-tray means being formed such that when said piece-tray means is in said closed position a partially assembled puzzle is fixedly between said pad on the bottom surface of said piece-

tray means and the pad on said assembly surface.

2. A jigsaw puzzle assembly apparatus as claimed in claim 1 wherein:

5 said assembly surface comprises a rectangular planar surface surrounded by four rails; and each of said piece trays comprises a rectangular planar surface surrounded by four rails, the rectangular surfaces of said piece trays being approximately one-half the size of the rectangular surface of said assembly surface.

10 3. A jigsaw puzzle assembly apparatus as claimed in claim 2 including four legs collapsably attached to said assembly surface.

15 4. A jigsaw puzzle assembly apparatus as claimed in claim 3 including closure means for maintaining said piece trays in said closed position.

5. A jigsaw puzzle assembly apparatus as claimed in claim 2 including:

20 two covers, each of said covers being suitable for enclosing the tops of said piece trays in a manner such that jigsaw puzzle pieces lying in said piece trays are fixedly held in said piece trays when said covers are enclosing the tops of said piece trays; and attachment means for releasably attaching said covers to said piece trays.

25 6. A jigsaw puzzle assembly apparatus as claimed in claim 5 including four legs collapsably attached to said assembly surface.

30 7. A jigsaw puzzle assembly apparatus as claimed in claim 6 including closure means for maintaining said piece trays in said closed position.

8. A jigsaw puzzle assembly apparatus as claimed in claim 4 including four legs collapsably attached to said assembly surface.

35 9. A jigsaw puzzle assembly apparatus as claimed in claim 1 wherein there are at least two piece-tray means, and two attaching means for attaching said piece-tray means to said assembly surface.
